UNITED STATES PATENT OFFICE.

JOHN J. MENDENHALL, OF CLEARWATER, FLORIDA.

DESIGN FOR A GRAPE-FRUIT, PARING, AND CORING KNIFE.

50,278.

Specification for Design.

Patented Feb. 6, 1917.

Application filed August 16, 1916. Serial No. 115,301. Term of patent 14 years.

To all whom it may concern:

Be it known that I, JOHN J. MENDENHALL, a citizen of the United States, residing at Clearwater, in the county of Pinellas and State of Florida, have invented a new, original, and ornamental Design for Grape-Fruit, Paring, and Coring Knives, of which the following is a specification, reference being had to the accompanying drawing, forming a part thereof.

Figure 1 is a perspective of a knife, showing my new design.

Fig. 2 is a side elevation of the same.

Fig. 3 is a sectional view on the line 3—3 of Fig. 2.

I claim:

The ornamental design for a grapefruit, paring, and coring knife, as shown.

JOHN J. MENDENHALL.
